Inventor
Emmanuel J. Grace
4 15th and

UNITED STATES PATENT OFFICE.

EMANUEL J. GRACE, OF ERIE, PENNSYLVANIA.

RIM-PUNCHING MACHINE.

Application filed July 12, 1922. Serial No. 574,478.

To all whom it may concern:

Be it known that I, EMANUEL J. GRACE, a citizen of the United States, residing at Erie, in the county of Erie and State of Pennsylvania, have invented new and useful Improvements in Rim-Punching Machines, of which the following is a specification.

The object of this invention is to punch wheel rims, particularly wheel rims provided with channels in which small rubber tires are placed. Heretofore the practice has been to punch these holes separately with the result that the rims are often shifted somewhat out of round and this slight shift or distortion varied the distances between the openings. With the present device all the holes are punched at once and the rim is held in proper contour at the time the punching is done so that the work is done uniformly and at the same time the entire punching is performed with one operation.

The invention is illustrated in the accompanying drawings as follows:

Fig. 1 shows a plan view, partly in section.
 Fig. 2 a section on the line 2—2 in Fig. 1.
 Fig. 3 a section on the line 3—3 in Fig. 2.
 Fig. 4 an end elevation of the machine.
 Fig. 5 a section on the line 5—5 in Fig. 6.
 Fig. 6 a section on the line 6—6 in Fig. 5.
 Fig. 7 a section on the line 7—7 in Fig. 8.
 Fig. 8 a section on the line 8—8 in Fig. 7.
 Fig. 9 a section on the line 9—9 in Fig. 4.
 Fig. 10 a detached plan view of the tripping lever.

1 marks the table on which the machine is mounted, 2 the legs supporting the table, 3 a hollow post extending up from the table, 40 and 4 a die platform. The platform has a series of radially extending slots 5. Die blocks 6 are slidably mounted in these slots. The die blocks have the extending flanges 7 (see Fig. 5) and plates 8 are arranged over these flanges and lock the die blocks in the grooves or slots 5. The die block has an opening 9 at its forward face in which the die 10 itself is secured, the die having an opening 11 into which the punch enters and having a rounded end conforming to the shape of the channel of the rim. An opening 12 extends vertically through the block at the rear of the opening 11 through which chips may be discharged. The die

itself is locked in place by a pin 13, the pin 55 being carried by a plate 13^a secured to the top of the block 6. A channel 14 is arranged below the groove 5 into which chips may enter from the opening 12 and openings 15 extend through the bottom of the platform 60 so that these chips may be discharged. Links 16 are pivotally mounted on the rear of the blocks by means of pins 17. The links are pivotally secured to an operating ring 18. The ring 18 has an annular tongue 65 19 which is rotatively mounted in an annular groove 20 in the platform. The links are secured in the ring by pins 21, these pins being readily lifted out of place so that different lengths of links may be inserted 70 to take care of different diameters of rims. A pinion 18^a is fixed on a shaft 18^b. The shaft is journaled in a bearing 18^c on the ring 18 and provided with an operating wheel 18^d. The pinion 18^a meshes with a 75 short rack 4^a on the platform 4. By turning the wheel 18^d it will readily be seen the ring 18 is rotated on the platform and this swings the links and draws the blocks 6 outwardly so as to release a rim from the 80 dies 10.

Punch blocks 22 are also mounted in the grooves 5. These punch blocks have the extending flanges 23 over which a plate 24 extends, thus securing the blocks in the 85 groove. Punch carriers 25 are screwed into the front faces of the blocks and the punches 25^a extend from the carriers in alignment with the die openings 11. Springs 26 are arranged in grooves 29 below the grooves 5, 90 the springs seating against studs 27 at their outer ends and against studs 28 carried by the blocks 22 at the inner ends, the effect of the spring being to push the blocks 22 inwardly so as to retract the punches. A 95 cam block 30 polygonally shaped having cam surfaces corresponding in number to the blocks 22 is arranged at the center of the machine. The cam block has a screw-threaded end 33 which is screwed into the bar 34. The bar 34 reciprocates in a bearing 34^a in the post 3, and a connecting rod 35 extends from the bar 34 to a crank 37. The crank 37 is mounted on a shaft 38. The shaft 38 is journaled in bearings 39, 100 these bearings being secured by bolts 40 to the underside of the table 1. It will readily be seen that as the shaft 38 is rotated the

cam mounting or bar 34 is reciprocated and the cam block 30 drawn down to force the punches outwardly and moved upwardly to relieve the punches.

5 In order that the shaft may make one operation and then be locked out I provide the following mechanism: A drive wheel 41 is mounted on an extension of the shaft 38 and is provided with clutch projections 42 which are hardened pieces secured to the wheel by bolts 42^a. These projections engage the detents 43 carried by a sliding collar 44, the block 43 being secured to the collar by bolts 43^a. The collar is slidingly mounted on the shaft 38 but locked against rotation by a spline 45. Springs 46 are mounted in pockets 47 in the collar 44 and rest against pins 48, the pins 48 being carried by a collar 49 arranged on the shaft 38. These springs tend to force the sliding clutch collar 44 forwardly or into engagement. The collar 44 has a lock-out pin 50 which in the rotation of the collar engages a cam surface 53 on a trip lever 51, the engagement of the cam surface moving the collar against the springs to the left as shown in Fig. 2 and throwing the clutch out of engagement. The trip lever is mounted on a pin 52. It is held upwardly and in the path of the pin 50 by means of a spring 54. A link 55 connects the trip lever 51 with a foot treadle lever 56 by means of which the trip lever may swing downwardly so as to be out of the path of the pin 50, thus permitting the clutch to set. The treadle lever is released after the starting of the operation so that when the shaft has made one complete operation it is locked out.

In the general operation of the device the dies are retracted by rotating the ring 18 as above described. A rim is dropped in place and the dies moved to position. This movement brings the links in alinement so that there is a straight-line thrust on the links. After the dies are set in place the treadle is depressed and the rotation of the

shaft 38 draws the cam block 30 downwardly thus expanding the punches and simultaneously punching all the holes of the rim.

What I claim as new is:—

1. In a rim punching machine, the combination of a plurality of radially and inwardly extending dies; a plurality of radially and outwardly movable punches operating in punching relation with said dies; an adjusting ring arranged outside of the dies; and means actuated by the rotation of said ring for simultaneously adjusting said dies. 50

2. In a rim punching machine, the combination of a plurality of radially and inwardly extending dies; a plurality of radially and outwardly movable punches operating in punching relation with said dies; an adjusting ring arranged outside of the dies; and means actuated by the rotation of said ring for simultaneously adjusting said dies comprising links connecting the ring and the dies. 60

3. In a rim punching machine, the combination of a plurality of radially and inwardly extending dies; a plurality of radially and outwardly movable punches operating in punching relation with said dies; an adjusting ring arranged outside of the dies; means actuated by the rotation of said ring for simultaneously adjusting said dies; and means for rotating the ring. 70

4. In a rim punching machine, the combination of a plurality of radially and inwardly extending dies; a plurality of radially and outwardly movable punches operating in punching relation with said dies; an adjusting ring arranged outside of the dies; means actuated by the rotation of said ring for simultaneously adjusting said dies; means for rotating the ring comprising a gear and segment; and means for rotating the gear. 80

In testimony whereof I have hereunto set my hand.

EMANUEL J. GRACE.
